(57) **CLAIM**

We claim the ornamental design for a collapsible height adjustable table, as shown and described.

DESCRIPTION

FIG. 1 is a top perspective view of a collapsible height adjustable table in a configuration of use, showing our new design.

FIG. 2 is a front elevation view thereof.

FIG. 3 is a rear elevation view thereof.

FIG. 4 is a right side elevation view thereof.

FIG. 5 is a left elevation view thereof.

FIG. 6 is a top plan view thereof.

FIG. 7 is a bottom plan view thereof;

FIG. 8 is a bottom perspective view thereof

FIG. 9 is a perspective view of the collapsible height adjustable table shown in a collapsed configuration.

FIG. 10 is a front elevation view of the collapsible height adjustable table shown in the collapsed configuration.

FIG. 11 is a rear elevation view of the collapsible height adjustable table shown in the collapsed configuration.

FIG. 12 is a right side elevation view of the collapsible height adjustable table shown in the collapsed configuration.

FIG. 13 is a left view elevation view of the collapsible height adjustable table shown in the collapsed configuration.

FIG. 14 is a top plan view of the collapsible height adjustable table shown in the collapsed configuration.

FIG. 15 is a bottom plan view of the collapsible height adjustable table shown in the collapsed configuration; and,

FIG. 16 is a bottom perspective view of the collapsible height adjustable table shown in the collapsed configuration.

(Continued)

The broken lines in the FIGS. 1-16 represent portions of the collapsible height adjustable table that form no part of the claimed design.
